UNITED STATES PATENT OFFICE.

HENRY H. C. DUNWOODY, OF WASHINGTON, DISTRICT OF COLUMBIA.

TELEPHONE TRANSMITTER AMPLIFIER AND REPEATER.

Application filed October 25, 1924. Serial No. 745,812.

To all whom it may concern:

Be it known that I, HENRY H. C. DUNWOODY, a citizen of the United States, residing at Washington, in the District of Columbia, have invented a certain new and useful Improvement in a Telephone Transmitter Amplifier and Repeater, of which the following is a specification.

My invention relates broadly to telephone apparatus, and more particularly to the construction of a device for varying the conductivity of an electrical circuit in accordance with speech vibrations for operation in conjunction with modulation systems, telephone transmission circuits, and amplifier and repeater system of telephonic currents.

One of the objects of my invention is to provide a telephone apparatus arranged to operate in circuit with a local source of energy of relatively large potential for producing relatively large fluctuations in energy in accordance with voice vibration to insure accuracy and distinctness in the transmission of speech.

Still another object of my invention is to provide a construction of telephone apparatus wherein sound vibrations cause variation in the current values in a circuit through the increase or decrease in pressure over a relatively large surface area and between a relatively large number of microphonic contacts.

Still another object of my invention is to provide a construction of sound vibration current controlling device wherein a pair of metallic discs are employed each having a plurality of instruck projections arranged to contact on opposite sides of a carbon disc providing a plurality of microphonic contacts through the sound vibration current controlling device for effecting the variation of a relatively large telephonic current.

Still another object of my invention is to provide a construction of sound control current variation device wherein a pair of magnetized plates having a plurality of instruck projections therein are arranged on opposite sides of a diaphragm forming a plurality of microphonic contacts with the surface of the diaphragm, the metallic plates being nor-

mally magnetized in such manner that the several projections consistently tend to attract each other through the said diaphragm, the plates being carried in such position that sound vibrations impressed thereagainst tend to vary the pressure between the plates and the diaphragm, causing variation in the energy controlled by the device.

My invention finds particular application in modulation circuits in telephone control systems, including line wire telephony, radio, and carrier wave line wire telephony, and the apparatus thereof operates effectively as a repeater and an amplifier of telephonic currents as will be hereinafter described in detail.

My invention will be more fully understood by reference to the accompanying drawings, wherein:

Figure 1 is a cross-sectional view taken through a telephone transmitter employing the apparatus of my invention; Fig. 2 is a plan view looking at one of the plates in the telephone apparatus of my invention; Fig. 3 is a partial cross-sectional view illustrating the disposition of the instruck projections over the surface of one of the plates; Fig. 4 is an enlarged cross-sectional view illustrating the arrangement of plates on opposite sides of the diaphragm and indicating the magnetized projections on the plates; Fig. 5 is a diagrammatic view illustrating the arrangement of the apparatus of my invention in a telephonic modulation control circuit; Fig. 6 is a diagrammatic view showing the apparatus of my invention employed for the amplification of telephonic currents; and Fig. 7 is a diagrammatic view showing the use of the apparatus of my invention in a repeater circuit for telephone systems.

Referring more particularly to the drawings, reference character 1 designates a housing for a telephone transmitter supported by lug 2 in the rear thereof enclosed by a front cover portion designated at 3 which carries the telephone mouth piece 4. Arranged within the transmitter casing 1 I provide an annular casing 5 having a screw

threaded portion 6 and a shoulder 7. The telephone apparatus abuts against the shoulder 7 and is secured in position by an annular screw threaded ring 8 suitably adjusted 5 in an axial direction by a socket wrench inserted in sockets 9. The telephone apparatus includes plates 10 and 11 each having a plurality of instruck projections 12 and 14 projecting from the plane of the plates but 10 integral with the material thereof. The plates 10 and 11 may be constructed of a magnetized nickel alloy permanently retaining a large amount of magnetism. Each plate is magnetized in such manner that the 15 projections of one plate assume a polarity opposite to the polarity of the projections of the other plate. The projections 14 of plate 10 are magnetized to form north poles, while the projections 12 of plate 11 are magnetized to form south poles. The plates 10 and 11 are positioned within the annular member 7 and supported by the smooth wall portion 15 thereof with a carbon diaphragm 16 disposed between the projections 12 and 14. The plates 10 and 11 are each provided with angle members 17 and 18 of insulated strip material bearing upon the peripheral surfaces of the carbon diaphragm 16 at points spaced one from another about the circumference thereof. The strips 17 and 18 have sufficient resilient qualities to normally position plates 10 and 11 in the desired relationship with respect to diaphragm 16. The securing means 17 and 18 also provide terminals for conductors 19 which pass into the telephone apparatus through a slot 20 into annular ring 5 and are led out to the associated circuits through cable 21. When employed as a telephonic 25 transmitter or modulator of telephonic currents, plates 10 and 11 are connected in circuit with a local source of energy 22 and a primary winding 23 of a modulation transformer 24. The secondary winding 25 of the transformer 24 delivers the modulated 30 energy to the control circuit as represented in Fig. 5. By reason of the relatively large energy which is safely handled through the multitude of microphonic contacts in the 35 telephone apparatus, I may amplify the energy at intervals in a line wire system as represented in Fig. 6 where incoming energy in winding 26 is transferred to a winding 27 and produces a response in telephone receiver 28. Telephone apparatus designated by reference character 29 is arranged adjacent the telephone receiver 28 where the telephone transmitter 30 collects sound vibrations reproduced by receiver 28 and 40 causes the sound vibrations to be impressed upon the microphonic contact system comprising plates 31 and 32 with the interposed carbon diaphragm 33. The plates 31 and 32 are connected in circuit with an independent source of energy 34 and a primary 45

winding 35 of transformer 36 causing energy of large amplitude to be delivered to secondary winding 37 from which it is passed to the line for transmission.

When employing the telephone apparatus of my invention in a repeater circuit I utilize an arrangement as illustrated in Fig. 7 where the line wire system 39 includes windings 40 and 41 inductively related to windings 42 and 43. The repeater comprises primary and secondary windings 44 and 45 connected in circuit with local battery 46. The windings operate upon solenoid plunger 47 which is positioned against plates 10 and 11 by means of adjusting device 48. The plates 10 and 11 include the plurality of microphonic contacts as hereinbefore described, and are placed on opposite sides of carbon diaphragm 16 and connected in circuit with local battery 49 and windings 42 and 43. The windings 44 and 45 are electrically arranged in regenerative relationship with respect to the plurality of microphonic contacts provided by plates 10 and 11 so that sound vibrations which impinge against metallic plate 11 cause the setting up of electrical impulses which are reamplified through windings 44 and 45 and then impressed on the line wire circuit 39.

It will be observed that I provide a great number of microphonic contacts in the telephone circuit enabling the energy which is to be usefully employed to be divided among a great many individual circuits and the energy of the several circuits integrated in a common control circuit for the transmission of telephonic energy.

While I have described my invention in certain particular embodiments, I desire that it be understood that modifications may be made and that no limitations upon the invention are intended other than are imposed by the scope of the appended claims.

What I claim and desire to secure by Letters Patent of the United States is as follows:

1. Telephone apparatus, comprising in combination an annular casing, an annular supporting member within said casing, and means carried within said annular supporting member for effecting a variation in an electrical current under the influence of sound vibration comprising a pair of permanently magnetized plates, a plurality of microphonic contacts carried by each of said plates, and a diaphragm intermediate said plates and cooperating with the microphonic contacts carried thereby, whereby said plates normally tend to attract each other and exert a predetermined pressure upon said diaphragm.

2. Telephone apparatus, comprising in combination an annular casing, an annular supporting member within said casing, a pair of plates carried in said supporting

member, each of said plates having a plurality of projections extending toward each other, a diaphragm positioned intermediate said plates and contacting with the exterior 5 surfaces of said projections, the projections on one of said plates being permanently magnetized in one polarity and the projec-

tions on the opposite plate being magnetized at the opposite polarity whereby said plates normally tend to attract each other and 10 exert a predetermined pressure upon said diaphragm.

HENRY H. C. DUNWOODY.
